UNITED STATES PATENT OFFICE.

HENRY WILSON POGUE, OF DECATUR, ILLINOIS.

ELECTRICAL CONNECTOR.

11,074,459.

Specification of Letters Patent. Patented Sept. 30, 1913.

Original application filed March 21, 1912, Serial No. 685,327. Division and this application filed January 26, 1913. Serial No. 744,704.

To all whom it may concern:

Be it known that I, HENRY W. POGUE, a citizen of the United States, and a resident of Decatur, in the county of Macon and State of Illinois, have invented a new and Improved Electrical Connector, of which the following is a full, clear, and exact description.

This invention relates generally to means for making electrical connections, and is more particularly adapted to a separable structure especially fitted for use in sad-irons.

The principal object of the invention is to provide a new and improved electrical connection made up of a plug and socket adapted for separation, the plug being adapted to be carried by the sadiron, and the socket being adapted to convey electric current to the plug which is in electrical connection with a heating coil carried by the iron.

Other objects and advantages following the use of the invention will appear as the description of the structure and operation proceeds.

Reference is to be had to the accompanying drawings forming a part of this specification, in which similar characters of reference indicate corresponding parts in all the views, and in which—

Figure 1 is a horizontal sectional view of the iron; Fig. 2 is a sectional view on the line 2—2 of Fig. 1; Fig. 3 is a vertical sectional view of the socket; while Fig. 4 is a perspective view of the clamp.

The subject matter described and claimed is a division of my pending application Serial No. 685,327, filed March 21, 1912.

The sadiron with which the electrical connection is especially adapted for use comprises the body 1 having a chamber 2 containing a heating coil 3 adjacent one side of the iron and contained within the chamber, a relatively movable member 4 being carried by the iron on the outer side thereof and adjacent the said heating coil 3. In the use of the iron the material to be pressed is passed between the heated wall of the iron and the movable member 4. Of course, the

size and shape of the iron may be varied, and, for that matter, the electrical connection to be described and claimed is equally adapted for use in other structures than that herein mentioned.

The bottom wall 5 of the iron is provided with spaced upstanding projections 6, between which is another projection 7. Each pair of projections 6 is substantially of the said height, and the projections 7 may or may not be the same height. The iron contemplates the use of two plugs, but since they are similar the specific construction of one will suffice for both. The plug comprises essentially the conducting member 8, preferably though not essentially of cylindrical form, having a knob 9 at its upper end, its lower end 10 being threaded, a shoulder 11 being provided intermediate the ends of the said member. These plugs are mounted on a holder 12, which is of a length sufficient to extend entirely across the said projections 6—7, as shown particularly in Fig. 2, the intermediate portion of the holder being provided with an opening 13 through which a securing screw 14 is adapted to be passed into engagement with a threaded opening 15 in the projection 7, the said holder, which is preferably of metal, being positioned between insulating elements 16—17. Adjacent each end of the holder is an opening 18, the diameter of the opening being substantially greater than the diameter of the said member 8 which constitutes the plug, the diameter being sufficient to receive a shoulder 19 carried on an insulating element 20, whereby the said plug may be maintained out of electrical contact with the body 1 of the iron; adjacent the under side of the said holder 12 is a second insulating element 21, the said member 8 being retained in position on the holder by means of a nut 22 on the threaded portion at the lower end thereof. Referring particularly to Fig. 2 it will be noted that when the holder with the conducting member 8 is secured in position no electrical connection between the body of the iron and the said member is provided, the fastening screw 14

serving to retain both of the plugs securely in position; furthermore, it will be noted that the spaces between the said pairs of shoulders or projections 6 provide pockets 23 for receiving the said nuts 22, whereby they are maintained in spaced relation to the body of the iron. These plugs are adapted to coöperate with a socket made up of two substantially similar portions held together by a suitable clamp or fastener, as shown particularly in Figs. 3 and 4. The two parts 24 of the socket are substantially similar, and each of them, on one side and adjacent one end, is provided with a pocket 25, the said pockets, when the parts are brought together, serving to contain the bent upper end 26 of the resilient conductor composed of the spaced sides 27. The lower ends of these sides are suitably curved, as at 28, whereby they may securely grip the knob 9 at the upper end of the conducting member 8 of the plug, whereby electrical connection is made, and in order to permit the play of the said sides 27 within the members 24 of the socket the intermediate portion of one side of each member is pocketed, as at 29. The upper end of each of the parts 24 is provided with an opening 30, which together form a passageway for the entrance of a wire 31 connected to one side of a suitable source of supply, the inner end of the said wire being in electrical contact, as at 32, with the said upper end 26 of the conducting element.

In order to maintain the said members 24 of the socket in coöoperative relation, a holder or clamp 33 is provided, the interior diameter of which is substantially equal to the exterior diameter of the socket, whereby it is adapted to embrace it, the upper and lower peripheral portions of the clamp being provided with projections 34 adapted to be bent into engagement in the notches 35 contained on the outer sides of the said members 24; in order to further the engagement of the said members, and to prevent relative movement, the adjacent sides thereof are provided with notches 36 and projections 37 adapted for interengagement, as shown particularly in Fig. 2.

In the use of the connection with a sad-iron the top of the chamber 2 therein is normally closed by a cover 38, having openings 39 extending therethrough, whereby the sockets may be entered into the chamber and into electrical connection with the said plug. If so desired, the under side of the said cover may be provided with an insulating element 40 to prevent, to some extent, an undue radiation of heat; the ends of the heating coil 3 are connected to the said plugs or conducting members 8 by means of wires 41—42, so that when it is desired to use the iron the insertion of the plugs into the openings 39 will provide current for

the said coil, thereby raising its temperature and heating the adjacent side of the iron.

Having thus described my invention, what I claim as new and desire to secure by Letters Patent is:—

1. The combination of a plug having an enlarged end, a socket made up of two pieces and containing a resilient conducting member having bent upper and lower ends and adapted to be connected to a wire, the inside of the socket being provided with pockets to receive the bent ends of the said resilient member.

2. A socket for use in making electrical connection, comprising two portions of substantially similar shape, a clamp surrounding the said portions on the outer side for holding them together, a substantially U-shaped resilient member of conducting material within the socket, the ends of the said member being curved and the inside of the said socket being provided with a plurality of pockets to receive the bent connecting portion and the curved ends of the resilient member.

3. In a structure such as described, the combination of a support, means for holding it in position, said means being intermediate the ends of the support, a plurality of plugs adjacent the ends of the support, insulating elements between the plugs and the supporting member, and means for securing the plugs to the support.

4. In an electric flatiron, the combination of a body member provided with a plurality of spaced projections, a supporting member extending across the projections, the middle projection being adapted to receive a fastening device, whereby the support may be held in position, a plurality of plugs carried by the support and adjacent the ends thereof and positioned between the end projections, means for maintaining the plugs out of electrical connection with the support, and means for securing the plugs to the support.

5. In means for making removable electrical connections, a socket adapted to receive an upstanding plug made up of two parts of substantially similar construction with means for holding them together, one end of the socket being provided with an opening whereby a wire may be entered therein, and a resilient substantially U-shaped conducting member within the socket, one end of the member being adapted to be connected to the said wire and the other end being adapted to engage the plug, the ends of the said conducting member being bent, and the interior of the socket being provided with pockets into which the said bent portions are adapted to engage, whereby separation of the parts is prevented.

6. In combination with a socket made up of parts of substantially similar shape, co-

operating projections and recesses on the parts, whereby they are positioned, notches on the outside of the said parts, and a substantially cylindrical clamp having projecting portions thereon embracing the said parts, the said projections engaging the said notches.

In testimony whereof I have signed my name to this specification in the presence of two subscribing witnesses.

HENRY WILSON POGUE.
